AIR CONDITIONING APPARATUS

Leroy Gale Huggins, Springfield, Mass., assignor
to Westinghouse Electric & Manufacturing
Company, East Pittsburgh, Pa., a corporation
of Pennsylvania

Application July 15, 1939, Serial No. 284,601

1 Claim. (Cl. 257—137)

My invention relates to air conditioning apparatus, more particularly to a self-contained air cooling unit, and it has for an object to provide improved apparatus of the character set forth.

A particular object is to provide a self-contained air cooling unit that may be mounted in the upper portion of a room or store—which may, for example, be suspended from the ceiling, set on top of a cabinet or storecase, or mounted on a bracket or platform attached to the wall.

A further object is to provide a compact arrangement of parts in a unit of the character set forth.

The above and other objects are effected by my invention as will be apparent from the following description and claim taken in connection with the accompanying drawings, forming a part of this application, in which:

Fig. 1 is a sectional view of my novel self-contained air cooling unit, taken on the line I—I of Fig. 2;

Fig. 2 is a front elevation, with parts broken away;

Fig. 3 is a perspective view of a modified form of my invention;

Fig. 4 is a perspective view of the modified unit with parts of the housing removed;

Fig. 5 is a front elevation, partly in section along the line V—V of Fig. 6; and,

Fig. 6 is an end elevation, partly in section along the line VI—VI of Fig. 5.

Referring first to the embodiment of my invention shown in Figs. 1 and 2, I show an air conditioning unit, more specifically a self-contained air cooling unit including a complete refrigerant circuit. The unit may also, as shown, comprise elements for heating and humidifying the air. The unit includes a housing 10, preferably of rectangular form, as shown, and of any suitable construction. The housing 10 is provided with a vertical partition 11, which extends between the front wall 12 and the rear wall 13 and divides the interior of the housing into an air cooling or air treating compartment 14 and a machine or unit compartment 15. The front wall 12 is formed with air inlet openings 16 and air outlet openings 17 communicating with the air treating compartment 14, the outlet openings being disposed above the inlet openings. Suitable vanes 18 may be disposed in the openings as is common in the art.

Within the cooling compartment 14, there is provided a vertical partition 19 which extends downwardly from the top wall in spaced and parallel relation to the front wall 12, and a hori-

zontal partition 20 which extends from the front wall, between the inlet openings 16 and the outlet openings 17, rearwardly to the partition 19. The partitions are secured in place in any suitable manner, as by means of right angle flanges, and form, together with adjacent wall portions of the cooling compartment, a fan discharge chamber 21 disposed adjacent the outlet openings 17, as shown in Fig. 1.

10 A fan 22 is provided in the upper portion of the cooling compartment between the partition 19 and the rear wall 13. It is disposed, as shown in Fig. 1, with its outlet 23 at the top and so as to discharge air in horizontal alignment with the outlet openings 17. The partition 19 is formed with an opening 24 in registry with the fan outlet 23. In the present embodiment, the fan casing is mounted on the partition 19 by connecting portions surrounding the outlet 23 and the opening 24. For example, the fan casing may be provided with flanges 25 overlying and attached to adjacent portions of the partition 19. The shaft of the fan is journaled in bearings 26, one of which is mounted on a bracket 27, attached to a partition 28 extending downwardly from the partition 20, and the other of which is mounted on a bracket 29 attached to the partition 11. An electric motor 30, mounted on the partition 19, drives the fan shaft through a suitable belt and pulley connection, as shown in Figs. 1 and 2.

Other air treating apparatus may be disposed in the lower portion of the compartment 14 between the evaporator and the rear wall. For example, a heating coil 36 may be disposed against the evaporator 33 and spray nozzles of any suitable type may be provided as indicated at 37. An expansion valve 38 for the refrigerant circuit may be located, for example, as shown in Fig. 1.

40 The machine compartment 15 houses the condensing unit which is enclosed in a fluid-tight casing 39. This unit contains the compressor, its drive motor, and the condenser. The evaporator 33, the compressor, the condenser and the expansion valve 38 are connected in refrigerant flow relation in a complete refrigerant circuit as is fully understood by any one skilled in the art, so that further description of the refrigerating system is deemed unnecessary.

45 When the unit is to be suspended from the ceiling, suspension bolts 40 are extended through the unit as shown in Fig. 1, the bolts extending through the channel iron base 35 and being provided with nuts 41 screw-threaded thereon for engaging the bottom of the unit.

Figs. 1 and 2—Operation

The refrigerating system operates in the well-known manner of such apparatus to supply refrigerant to the evaporator 33. In the condensing unit, the refrigerant is compressed by the compressor and liquefied in the condenser. The liquid refrigerant is then conveyed through a suitable conduit (not shown) to the expansion device 38, wherein the pressure of the refrigerant is reduced and the flow thereof is regulated. The refrigerant is then conveyed through the evaporator 33 in which it serves to extract heat from the air flowing through the evaporator and is thereby vaporized. The vaporized refrigerant is returned to the condensing unit for recirculation.

The fan 22, when driven by the motor 30, is operative to effect circulation of air through the cooling compartment as follows: Air from the room in which the unit is placed is drawn into the cooling compartment horizontally through the inlet opening 16 and the filter 31. The air stream flows horizontally through the evaporator and also through the heating coil 36. The air then flows upwardly to the inlet of the fan 22, from which it is discharged at a relatively high velocity through its outlet 23 and the partition opening 24 into the discharge or plenum chamber 21. From the latter, the air is discharged into the room through the outlet openings 17.

The stream of air discharged horizontally from the outlet openings 17 is disposed well above the heads of the people in the room. This stream of air extends for a distance, for example, of twenty feet and is effective to produce circulation of air in the room. Air from the room is drawn into the inlet opening 16 without producing any draft.

The self-contained air cooling unit or air conditioning unit shown in Figs. 1 and 2 is especially adapted for mounting in the upper portion of a room, and is adapted for mounting in any one of several different ways. For example, it may be suspended from the ceiling by means of the suspension bolts 40. Also, it may be set on top of a cabinet or case in a store. It may also be mounted on a platform attached to the wall. The unit may be located with its rear wall 13 disposed against the wall of the room, inasmuch as the air is drawn into the unit and discharged therefrom through its front wall.

Figs. 3 to 6

In Figs. 3 to 6, I show a modified form of my invention which incorporates some suggestions of John L. Ditzler. The unit shown in these figures is at present a preferred embodiment suitable for somewhat smaller capacities than the first embodiment.

This unit comprises a housing 50 which may be suspended from the ceiling by means of suspension bolts 51 or which may be set on any suitable supporting surface, such as a platform or the top of a cabinet or case. The housing is provided with a partition 52 extending between the front wall 53 and the rear wall 54, and dividing the interior of the housing into a cooling compartment 55 and a machine compartment 56, disposed side-by-side, similar to the embodiment shown in Figs. 1 and 2.

Within the cooling compartment 55, a vertical partition 57 extends downwardly from the top wall in spaced and parallel relation to the front wall 53. A horizontal partition 58 extends from the bottom of the partition 57 to the front

of the housing. The partitions 57 and 58 form, together with the adjacent wall portions of the cooling compartment, a discharge chamber 59.

As will be apparent from Figs. 4 and 6, the front of the cooling compartment is open, providing an inlet opening 61 and an outlet opening 62, the inlet opening being disposed beneath the outlet opening, and the division between the two openings being formed by the partition 58. 10 A common grill element 63 is removably mounted in the inlet and outlet openings, being provided with one set of louvers 64 extending across the inlet opening 61, and a second set of louvers 65 extending across the outlet opening 62.

15 A centrifugal fan 66 is disposed in the upper portion of the cooling compartment, between the partition 57 and the rear wall 54. As in the first embodiment, the fan 66 is disposed with its axis extending horizontally and with its outlet disposed on the upper side so as to discharge horizontally into the discharge chamber 59 and through the outlet 62. The casing of the fan 66 is supported by connecting it at the outlet, for example, by bolting it to right angle flanges of the partition 57, the partition 58 and the top of the housing 50. The fan shaft is journaled in bearings 67 mounted on brackets attached to the left-hand side wall and to the partition 52, respectively, as shown in Fig. 5. The right-hand end of the fan shaft extends through the partition 52 into the machine compartment 56, and a pulley 69 is mounted on the projecting portion. A motor 70 is provided for driving the same. It may be located in either compartment, but it is preferably located in the cooling compartment in order that it may be properly cooled. As shown, it is mounted on the partition 52 by means of a bracket 71 and its shaft extends through the partition into the machine compartment. A pulley 72 is mounted on the projecting portion of the motor shaft, and it is disposed in alignment with the pulley 69. A belt 73 is mounted on the two pulleys, so that the fan is driven by the motor through the pulleys 69 and 72 and the belt 73.

40 A filter 74 of any suitable type is disposed across the inlet opening 61 on the inside of the grill element 63. It is adapted to be inserted and removed through the inlet opening 61 when the grill element is removed, and it is retained in position in any suitable manner, for example, as shown in Fig. 6.

45 A refrigerant evaporator 75 is disposed in a vertical plane and mounted in horizontal alignment with the inlet opening 61, as shown in Fig. 6. It may be, as shown, set in a drain pan 76. The evaporator 75 may be, as shown, of the well-known type comprising serpentine coils and transverse fins or plates providing extended heat transfer surface. A partition 77 extending between the partition 58 and the top of the evaporator 75 may be provided to prevent the by-passing of air over the top of the evaporator, and a similar partition 78 may be provided to close the space between the left-hand end of the evaporator and the left-hand side wall. Here again, provision may be made for by-passing air around the evaporator as desired. The expansion valve for regulating the flow of refrigerant to the evaporator is shown at 79 and may be of any suitable type known in the art. I have also shown a heat transfer device 81 for transferring heat from the liquid refrigerant flowing to the expansion valve to the vaporized refrigerant leaving the evaporator through the suction conduit 82. The use

of such a heat transfer device is, of course, optional.

A heating element may be provided within the air-treating or cooling compartment 55, preferably in the path of the air between the evaporator and the fan. As shown on the drawing, a heating element 83 is disposed horizontally immediately below the fan casing and is suspended by two sheet metal members or hangers 84, which also serve to prevent by-passing of air 10 around the heating element.

In the present embodiment, a motor compressor unit 85 of the horizontally enclosed type is disposed within the machine compartment 56. The condenser 86, in this case, is of the double tube type and is shown as wound helically around a portion of the motor compressor unit. The condenser is water cooled, the water being supplied through a conduit 87 and controlled by a regulating valve 88. A suitable electrical control device 89 may be mounted on the rear wall 54 within the machine compartment 56. It will be apparent, however, that the electrical control may be of any suitable type so far as the present invention is concerned.

The evaporator 75, the motor compressor unit 85, the condenser 86, and the expansion valve 19 are connected in a complete refrigerant circuit of the conventional mechanical compression type. Inasmuch as systems of this type are well known in the art, it is thought unnecessary to describe the detail connections. However, it is to be understood that the entire refrigerant circuit is enclosed within the housing 50, so that the refrigerating system may be completed and fully charged at the factory and shipped with the refrigerant charge therein. Accordingly, it is unnecessary to provide the services of a skilled refrigeration service man to install this unit.

Figs. 3 to 6—Operation

The refrigerating system operates in the usual manner of such apparatus, the refrigerant vapor being compressed by the motor compressor unit 85, condensed in the condenser 86, conveyed through suitable connecting conduits to the expansion valve 19 which regulates the flow and reduces the pressure thereof. The refrigerant is then admitted to the evaporator 75 wherein it is vaporized in extracting heat from the air flowing over the surfaces of the tubes and fins. The refrigerant vapor is returned to the motor compressor unit for recirculation.

The fan 66 provides circulation of air therethrough as follows: Air from the room is drawn through the inlet opening 61, the filter 74 and

the evaporator 75, through each of which the air flows substantially horizontally. The air then flows over the motor 70 to cool the same, upwardly in contact with the heating element 83 to the inlet of the fan. The air is then discharged by the fan horizontally through its outlet into the discharge chamber 59, from which it is discharged through the outlet 62. The provision of the discharge chamber 59 allows the air to be discharged from the outlet 62 at a velocity lower than that at which it is discharged from the fan.

As in the first embodiment, the discharge of the air through the outlet 62 produces a jet or stream extending across the top of the room at an elevation above the heads of the people. This stream of air produces circulation of air in the room and also entrains a certain portion of unconditioned air, so that the air reaching the people in the room is tempered.

While I have shown my invention in several forms, it will be obvious to those skilled in the art that it is not so limited, but is susceptible of various other changes and modifications without departing from the spirit thereof, and I desire, therefore, that only such limitations shall be placed thereupon as are specifically set forth in the appended claim.

What I claim is:

- 30 An air conditioning unit adapted to be mounted in the upper portion of a room and comprising a housing having an air inlet and an air outlet in a vertical wall thereof, the inlet being disposed beneath and adjacent said outlet, a partition disposed in parallel and spaced relation to said vertical outer wall and having an opening opposite to the air outlet therein, a horizontal partition extending from said vertical outer wall, between said outlet and said inlet, to said vertical partition to form therewith a discharge chamber adjacent said air outlet, a centrifugal fan having its outlet connected to said opening and disposed to discharge air horizontally therethrough into said discharge chamber, said inlet extending above the lowermost part of said fan, a heat transfer element disposed adjacent said fan and in horizontal alignment with said air inlet, the parts being constructed and arranged so that air entering through said inlet flows horizontally through said heat transfer element, then to said fan, and is discharged horizontally from said fan outlet, and flows horizontally through said discharge chamber and said air outlet.
